Primary Examiner — Susan Bennett Hattan*Assistant Examiner* — Landon Thomas Cassell(74) Attorney, Agent, or Firm — Wood, Phillips, Katz, Clark & Mortimer(57) CLAIM

The ornamental design for a lactation breast massager, as shown and described.

DESCRIPTION

FIG. 1 is a front, side, and top perspective view of a lactation breast massager showing my new design;

FIG. 2 is an elevation view thereof from the side opposite that in FIG. 1;

FIG. 3 is an elevation view thereof from the same side as in FIG. 1;

FIG. 4 is a front elevation view thereof;

FIG. 5 is a rear elevation view thereof;

FIG. 6 is a top view thereof; and,

FIG. 7 is a bottom view thereof.

1 Claim, 4 Drawing Sheets
